UNITED STATES PATENT OFFICE.

ADOLPH F. BREWER, OF NEW YORK, N. Y.

CLOTHES-LINE COUPLING.

SPECIFICATION forming part of Letters Patent No. 289,334, dated November 27, 1883.

Application filed May 31, 1883. (No model.)

To all whom it may concern:

Be it known that I, ADOLPH F. BREWER, of the city of New York, county and State of New York, have invented a new and Improved 5 Clothes-Line Coupling, of which the following specification is a full, clear, and exact description.

This invention relates to a new clothes-line coupling; and it consists in the combination 10 of a perforated sleeve having shoulders to form spring-jaws with a ring encircling said spring-jaws, and with a set-screw, all being so constructed that the distance between the contiguous faces of the spring-jaws is less than the 15 distance between the two long sides of the sleeve, all as hereinafter more fully pointed out.

In the accompanying drawings, Figure 1 is 20 a perspective view of my improved clothes-line coupling. Fig. 2 is a longitudinal central section of the same on the line *x*-*x*, Fig. 3; and Fig. 3, a transverse section on the line *y*-*y*, Fig. 2.

Similar letters of reference indicate corresponding parts in all the figures.

The letter *A* represents my improved clothes-line coupling, composed, principally, of a sleeve, *a*, ring *b*, and set-screw *c*. The sleeve *a* is composed of two long and two short sides, 30 one of its short sides being perforated at *e* to admit one end of clothes-line *B*, while the other shortside is open and terminates in two spring-jaws, *d* *d'*, forming shoulders *g* with long sides of sleeve *a*. In this way the distance between the 35 two long sides of sleeve *a* is considerably less than the distance between the contiguous faces of the spring-jaws. To the lower jaw, *d*, is rigidly attached, by screw *f*, the ring *b*. This ring encircles both jaws *d* *d'*, and is considerably larger in diameter than their com-

bined thickness, so as to allow for the up-and-down play of the upper jaw, *d'*. The set-screw *c* passes through the ring *b*, and by turning it in either direction the jaws *d* *d'* are either allowed to separate or are pressed together. 45

In operation, one end of the clothes-line *B* is passed through the hole at *e* and knotted, to prevent withdrawal. The other end is drawn through the groove of the spring-jaws, and is likewise knotted. The set-screw *c* is then 50 turned to press the spring-jaws together. In this way the line *B* may be clamped at any point desired, and thus its length may be adjusted. By having the distance between the 55 two long sides of sleeve *a*, sufficient room is left between said long sides for the formation of the knots in line *B*.

I do not claim to have invented the combination of a pair of spring-jaws with an encircling ring adapted to compress said spring-jaws, as such a construction is shown in Patent No. 193,566, granted to J. H. Snyder, July 24, 1877; but 60

I do claim— 65
In a clothes-line clamp, the combination of sleeve *a*, perforated at *e*, and having shoulders *g*, to form spring-jaws *d* *d'*, with the ring *b*, encircling said spring-jaws, and with the set-screw *c*, all constructed, substantially as described, so that the distance between the contiguous faces of the spring-jaws *d* *d'* is less than the distance between the two long sides of sleeve *a*, substantially as and for the purpose specified. 70

ADOLPH F. BREWER.
